UNITED STATES PATENT OFFICE.

CHESTER T. ALLCUTT, OF PITTSBURGH, PENNSYLVANIA, ASSIGNOR TO WESTINGHOUSE ELECTRIC & MANUFACTURING COMPANY, A CORPORATION OF PENNSYLVANIA.

HIGH-FREQUENCY DIELECTRIC FURNACE.

Application filed October 27, 1923. Serial No. 671,113.

To all whom it may concern:

Be it known that I, CHESTER T. ALLCUTT, a citizen of the United States, and a resident of Pittsburgh, in the county of Allegheny and State of Pennsylvania, have invented a new and useful Improvement in High-Frequency Dielectric Furnaces, of which the following is a specification.

My invention relates to electric heating and particularly to heating by means of a high-frequency electric field.

The object of my invention is to provide a system of, and means for, heating by the use of a high-frequency electric field.

15 In practicing my invention, I provide a source of high-frequency electric current and connect the terminals thereof to two electrodes between which is located a member of imperfect dielectric material which 20 becomes heated when subjected to the high-frequency electric field produced between the electrodes.

In the single sheet of drawings,

25 Figure 1 is a schematic view of a high frequency source of electric energy operatively associated with a furnace, illustrated in section, embodying my invention,

Fig. 2 is a schematic view of a modified form of high-frequency system embodying 30 my invention,

Fig. 3 is a view, in section, of a further modification of a device comprising a part of a system embodying my invention,

Fig. 4 is a view, in section, of another 35 modification of a device embodying my invention,

Fig. 5 is a schematic view of a still further modification of a high-frequency heating system, and

40 Fig. 6 is a schematic view, in side elevation, of a commercial application of high frequency dielectric heating.

Referring more particularly to Fig. 1 of the drawing, a source of alternating current 45 is here indicated by the conductors 11 that are connected to the terminals of the primary winding 12 of a suitable transformer. The secondary winding 13 is connected to the terminals of a condenser 14, of suitable 50 type, and the connections employed are such as to provide a source of sustained electric current of high frequency and of high voltage delivered to the conductors 15 and 16.

55 A crucible 17 of any suitable or convenient form has located thereon an enclosing

electrode 18 that is electrically connected to the conductor 16. A mass 19, of a material to be heated, is located within the crucible 17 and is electrically connected to the conductor 15.

60 The crucible 17 is made of a material that is an imperfect dielectric and which, when subjected to the action of the high-voltage alternating electric field existing between the mass of material 19 and the outer electrode 18 when the system is energized, is heated by the loss of energy in the dielectric material itself. As is well known, the energy loss in a member of imperfect dielectric material when subjected to an alternating electric field is dependent upon the geometrical dimensions of the member, the material of which it is made, the frequency of the field and the square of the applied voltage.

65 In general, this loss is relatively small for such members where the dimensions of the crucible are relatively limited and it is, therefore, advisable to employ a frequency that is as high as is commercially possible and a voltage that is as high as is practicable.

70 The crucible 17 may, for instance, be made of clay, porcelain or glass that will be heated when subjected to the action of a high frequency and high-voltage electric field and that will, at the same time, serve as a container for materials to be heated therein, the heat being generated directly in the crucible 75 of dielectric material and imparted to the material located therein by conduction.

75 Dielectric materials of the ordinary kind that may be employed as containers are usually relatively poor conductors of electricity when cool but become much better conductors when heated, that is, they have a 80 relatively high negative temperature coefficient of resistivity. It is advisable, therefore, to provide some means for counteracting this effect, which would result in a tendency of the current flowing through a member of dielectric material to concentrate at any point that had a relatively high loss, such as might be caused by a defect in the material. Such means may be provided by a condenser or by an air gap placed in series 85 relation to the imperfect dielectric and such means is illustrated more particularly in Fig. 2 of the drawing, where the crucible 17 has an electrode 21 surrounding it but spaced therefrom. This construction, of 90

course, reduces the inherent capacity of the structure, but provides means for insuring that the current traversing the member of imperfect dielectric material shall be substantially uniform over substantially its entire surface since the air between the members 17 and 21 is a relatively perfect dielectric and there will be no tendency for the current to concentrate at certain points.

10 The same effect may be obtained by employing a member of relatively perfect solid, dielectric material between the crucible and the outer electrode. This is illustrated more particularly in Fig. 3 of the drawing, 15 wherein the crucible 22 for containing the mass of material to be heated is made of glass and is surrounded by a crucible 17, of quartz, an electrode 18 being fitted closely around a portion of the peripheral surface 20 of the quartz crucible 17. As quartz is a much better dielectric than glass, it will operate to prevent what may be termed local hot spots in the crucible 22 and insure substantially uniform distribution of current 25 traversing the member 22.

The crucible 17 of quartz, illustrated in Fig. 3 of the drawing, will also be heated when subjected to the action of a high voltage and high frequency electric field and 30 will therefore assist in increasing the temperature of the mass of material located within the inner crucible 22.

A structure that may be used in heating non-conducting materials is illustrated in Fig. 4. A conducting electrode 23 is inserted in crucible 24 of dielectric material, but is spaced therefrom by a mass of material 25 to be heated. A second conducting electrode 26 surrounds the crucible but is 35 spaced therefrom as in the structure shown in Fig. 2. When a source 13, of high-frequency electromotive force, is connected to the electrodes 23 and 26, the losses in the mass 25 of non-conducting material to be 40 heated, supplemented by such losses as may occur in the dielectric crucible 24, will cause the material in the crucible to attain the desired temperature.

In Fig. 5, I have illustrated a relatively narrow and elongated crucible or container 27 of a suitable imperfect dielectric material. Electrodes 28 and 29 connected to the terminals of the source of high frequency and high voltage current, here illustrated 50 as a secondary coil 13 of a transformer, are of relatively large surface area and may be located a relatively short distance apart, thereby increasing the capacitance of the device and, therefore, the power loss in the crucible 27. This modification is particularly adapted for use in case the material contained in the crucible is non-conducting.

In Fig. 6, I have illustrated schematically one form in which the system embodying 55 my invention may be employed commer-

cially. A sheet or strip 31, of high grade paper, such as is employed in the making of condensers, is caused to travel over suitably spaced supporting means 32 and 33 by any actuating means (not shown) and the source of high-frequency and high-voltage current is connected to a stationary electrode or terminal 34 in the form of a plate and to a rotatable wheel electrode 35 upon which the strip or sheet of paper may rest while moving from the support 32 to the support 33. Paper of this kind is an imperfect dielectric, particularly when it contains moisture and when subjected to the action of a high-frequency electric field is heated and any moisture that may be in the paper will be driven out thereby and the paper will, therefore, be thoroughly dry, if immediately incorporated in the condenser and suitably protected against reabsorption of moisture. This method is particularly advantageous because of the fact that the losses and consequent heating of the paper are more or less restricted to such portions of the paper as contain undesirable moisture. Portions of the paper that do not contain an undesirable quantity of moisture will have relatively low dielectric losses and will be but slightly heated. Obviously, a saving in power will result. Furthermore, this method permits of very rapid drying without danger of overheating since the losses diminish as the paper dries and overheating is thereby automatically prevented.

Where I have referred to a source of sustained electric current of high-frequency, I include frequencies not less than those usually employed in radio telegraphy and radio telephony and such higher frequencies as may be commercially produced for such applications. A sustained alternating current of high frequency is particularly applicable for my purpose, as the discharge from a series of high-frequency wave trains, such as produced by an oscillatory spark discharge, will not produce the desired heating effects.

Various modifications and changes may be made herein without departing from the spirit and scope of the invention, and I desire, therefore, that only such limitations shall be placed thereon as are imposed by the prior art or are specifically set forth in the appended claims.

I claim as my invention:

1. In combination, a pair of terminal members, a member of imperfect dielectric material therebetween, and a source of high-frequency current supply connected to said terminal members.
2. In a heating system, a container of imperfect dielectric material, and means for subjecting said container to the action of a high-frequency current.
3. In an electric furnace, in combination,

a dielectric member, and means for subjecting said member to the influence of an electric field of relatively high frequency and of relatively high voltage.

5. 4. In an electric furnace, in combination, a dielectric member, and means for subjecting said member to the influence of a high-frequency electric field.

5. In an electric furnace, in combination, 10 a dielectric member and a source of high-frequency electromotive force having its terminals electrically connected to opposite sides of said dielectric member.

6. In combination, a member of imperfect 15 dielectric material, a pair of terminal members, a source of high-frequency current supply connected to said terminal members, and means for insuring a substantially uniform energy loss throughout the mass of said 20 dielectric member.

7. In combination, a member of imperfect dielectric material, a pair of terminal members, a source of high-frequency current supply connected to said terminal members, and 25 means for insuring a substantially uniform current density throughout the mass of said dielectric member under all conditions of operation.

8. In combination, a member of imperfect 20 dielectric material, a source of high-frequency current supply, a pair of terminal

members connected to said terminals, operatively associated with said member of dielectric material, and means having a higher dielectric strength than said first 35 named dielectric material interposed between said terminal members and said member of imperfect dielectric material.

9. The method of heating a mass of material which comprises subjecting a member 40 of imperfect dielectric material to a high-frequency electric field and causing the heat generated therein to heat said mass of material.

10. The method of heating a mass of material located in a container of imperfect dielectric material which comprises subjecting the container to the action of a high-frequency field.

11. The method of heating a mass of material located in a container of imperfect dielectric material which comprises connecting one terminal of a high-frequency circuit to said mass of material, connecting the other terminal of said circuit to a terminal 55 member located outside of said container, and energizing said circuit.

In testimony whereof, I have hereunto subscribed my name this 22nd day of October, 1923.

CHESTER T. ALLCUTT
